W. B. HAYDEN.
DIRECT ACTING STEAM ENGINE.

No. 95,225.

Patented Sept. 28, 1869.

United States Patent Office.

WILLIAM B. HAYDEN, OF COLUMBUS, OHIO.

Letters Patent No. 95,225, dated September 28, 1869;

IMPROVEMENT IN DIRECT-ACTING STEAM-ENGINES.

The Schedule referred to in these Letters Patent and making part of the same.

To all whom it may concern:

Be it known that I, WILLIAM B. HAYDEN, of Columbus, in the county of Franklin, and State of Ohio, have invented a new and improved Direct-Action Engine; and I do hereby declare that the following is a full, clear, and exact description thereof, reference being had to the accompanying drawings, making part of this specification, in which—

Figure 1, plate 1, is a vertical section, taken longitudinally through the centre of my improved engine.

Figure 2, plate 1, is a central cross-section through the piston.

Figure 3, plate 2, is a cross-section, through the centre of the engine.

Figure 4, plate 2, is a top view of the cylinder, with the steam-chest removed.

Similar letters of reference indicate corresponding parts in the several figures.

The object of this invention is to operate a balanced slide-valve by the alternate action upon its opposite sides, of the pressure of steam, received from a piston, which is chambered and provided with inwardly-opening valves, as will be hereinafter explained.

To enable others skilled in the art to understand my invention, I will describe its construction and operation.

In the accompanying drawings, fig. 1—

Y represents the cylinder of the engine; R, a piston, working therein.

Q is the steam-chest, and E, the slide-valve working therein.

A is the steam-pipe, through which steam passes by way of the branch parts B, into the steam-chamber K, and acts against the ends of the slide-valve E, so as to balance this valve.

The valve E is provided with stems F F, which pass, steam-tight, through the heads G G, into chambers H H, and against the reciprocating-plugs D D, which work in these chambers.

C C are steam-passages, which are enlargements of steam-chamber K, and which communicate with the cylinder Y on opposite ends of the piston R, by way of the ports x x; and

I' is another enlargement of chamber K, which forms a communication between this chamber and the exhaust-pipe I.

O O are ports, passing from the interior of the cylinder Y into the chambers H H, on the outer sides of the small plugs or pistons D D; and

P P are ports, which pass from the ports x x into the chambers H H, on the inner sides of the plugs or pistons D D.

The ports O pass through connections M M, so as

to cross the ports X X, which connections will not, however, interfere with the free passage of steam through said ports X.

The piston R is made hollow, and at each end of it a valve, L, is applied, so as to open inwardly.

This chambered piston has slots T T cut through it, for the purpose of forming communication between the interior of the piston and the spaces H H, through ports O O, when the piston is at the termini of its strokes.

The tappet T, at the end of the steam-chest, is arranged in line with the plugs or pistons D, and designed for starting when the engine is full of condensed steam.

In fig. 1, the piston R is represented as having completed a stroke from the left to the right, with the slot T under the port O, which allows steam that was taken into the piston, at the opposite or left-hand end of the cylinder, to pass into the space H, and to move the plugs D D and valve E to the position indicated in fig. 1, thereby exhausting the left end of the cylinder, through ports X I' I, and letting the steam into the cylinder, on the right-hand side of the piston.

When the piston is at the termini of its strokes, the expansion of the steam in its chamber will, by its elasticity, keep the valve E moving, and prevent this valve from bounding back, after the cylinder is exhausted.

It will be seen that during the passage of the piston from one end to the other of the cylinder, the plug D, on that side of the valve E, on which steam passes to the cylinder, will be balanced by the steam entering its chamber H, through ports P and O, thus preparing it to be easily moved by the steam from the interior of the piston at the proper time.

When the piston completes its left-hand stroke, steam from its chamber will pass up through port O, into chamber H, and move the plugs D D and valve E to the right, thereby causing steam to exhaust from the right-hand side of the piston, through ports X I' I, and admitting steam to the cylinder on the left side of the piston.

Immediately succeeding the opening of the exhaust-ports on one side of the engine, the valve L, on the same side of the piston, will be shut, and the valve on the opposite side will be opened, and kept open until the piston makes another stroke. In this way, the steam which is used to move the slide-valve is let into the piston.

Having described my invention,

What I claim as new, and desire to secure by Letters Patent, is—

1. A balanced slide-valve, E, constructed with stems F F upon it, and arranged to operate in com-

bination with independent plugs or pistons D D, substantially as described.

2. The ports O O, for admitting steam on the outer ends of the plugs D, in combination with ports P P, for admitting steam on the opposite sides of these plugs, arranged substantially as described.

3. The hollow piston R, provided with inwardly-opening valves L L, and with slots T, and adapted to operate a balanced slide-valve, substantially as described.

4. Steam-spaces C C, as enlargements of the steam-chamber K, communicating with the ports X and I, substantially as described.

5. The ports O P, leading into the chambers H, containing the plugs D, substantially as described.

6. Chamber K, containing valve E, chambers H H, containing plugs D D, in combination with ports leading from said chambers into the steam-cylinder Y, and with a chambered piston, R, substantially as described.

WM. B. HAYDEN.
